UNITED STATES PATENT OFFICE.

MARTIN ARNS, OF SYRACUSE, NEW YORK.

DESIGN FOR A CLOTHES-SPRINKLER.

SPECIFICATION forming part of Design No. 35,103, dated September 17, 1901.

Application filed August 10, 1901. Serial No. 71,663. Term of patent 8½ years.

To all whom it may concern:

Be it known that I, MARTIN ARNS, a citizen of the United States, and a resident of Syracuse, in the county of Onondaga, in the State of New York, have invented a new Design for a Clothes-Sprinkler, of which the following, taken in connection with the accompanying drawings, is a full, clear, and exact description.

10 The leading or material feature of my new design consists of the perforated hollow shell A, having the stem B extending therefrom, as shown in the accompanying drawings, in which—

15 Figure 1 is a side view of the clothes-sprinkler, and Fig. 2 is a transverse section on line X X in Fig. 1.

The shell A is of elliptical shape and is provided with a plurality of perforations a a, distributed in the greater portion thereof, 20 and the stem B extends from one end of the shell and is arranged in line with the longer axis of the same.

What I claim as new, and desire to secure by Letters Patent, is—

25 The design for a clothes-sprinkler, as herein shown and described.

In testimony whereof I have signed my name to this specification in the presence of two subscribing witnesses.

MARTIN ARNS.

Witnesses:

J. J. LAASS,
WM. HAWLEY.
